Primary Examiner — Lilyana Bekic*Assistant Examiner* — Carson Jean Bendel(74) *Attorney, Agent, or Firm* — Foley Hoag LLP;
Stephen J. Kenny; Nicole A. Bustos-Pomerantz(57) **CLAIM**

The ornamental design for a vacuum generating head as shown and described.

DESCRIPTION

FIG. 1 is a front view of the vacuum generating head showing my new design.

FIG. 2 is a right view thereof.

FIG. 3 is a rear view thereof.

FIG. 4 is a left view thereof.

FIG. 5 is a bottom view thereof.

FIG. 6 is a top view thereof; and,

FIG. 7 is a front perspective view thereof.

The broken lines in the drawings depict portions of the vacuum generating head, and form no part of the claimed design.
